DESIGN FOR AN AIRPLANE

Donovan R. Berlin, Detroit, Mich.

Application September 30, 1942, Serial No. 108,363

Term of patent 3½ years

To all whom it may concern:

Be it known that I, Donovan R. Berlin, a citizen of the United States, residing at Detroit, State of Michigan, have invented a new, original, and ornamental Design for an Airplane, of which the following is a specification, reference being had to the accompanying drawing forming a part thereof.

Fig. 1 is a front elevational view of an airplane showing my new design as it appears with the landing gear in extended position.

Fig. 2 is a top plan view.

Fig. 3 is a side elevational view with the landing gear in extended position; and

Fig. 4 is an enlarged bottom perspective view thereof with the landing gear retracted as in flight.

I claim:

The ornamental design for an airplane as shown.

DONOVAN R. BERLIN.
